US00D943061S

(12) **United States Design Patent** (10) **Patent No.:** **US D943,061 S**
(45) **Date of Patent:** **** Feb. 8, 2022**

(54) **FUEL NOZZLE**

(71) Applicant: **Marine Turbine Technologies, LLC**,
Franklin, LA (US)

(72) Inventors: **Ted Lee McIntyre, II**, New Iberia, LA
(US); **Nelson Joseph Geoffroy**, Erath,
LA (US); **Marc G. Boulanger**, Erath,
LA (US)

(73) Assignee: **Marine Turbine Technologies, LLC**,
Franklin, LA (US)

(**) Term: **15 Years**

(21) Appl. No.: **29/779,152**

(22) Filed: **Apr. 16, 2021**

Related U.S. Application Data

(63) Continuation of application No. 16/371,753, filed on
Apr. 1, 2019, now Pat. No. 11,060,460.

(57) **CLAIM**

The ornamental design for a fuel nozzle, as shown and
described.

DESCRIPTION

FIG. 1 is a left side elevation view of a fuel nozzle showing
our new design;

FIG. 2 is a right side elevation view thereof;

FIG. 3 is a top plan view thereof;

FIG. 4 is a bottom plan view thereof;

FIG. 5 is a front elevation view thereof;

FIG. 6 is a rear elevation view thereof; and,

FIG. 7 is a top and front perspective view thereof.

The broken lines shown represent portions of a fuel nozzle
and form no part of the claimed design.

1 Claim, 4 Drawing Sheets
